TIME INDICATING SYSTEM

Emil N. Anderson, Oak Park, Ill., assignor to
American Telephone and Telegraph Company,
a corporation of New York

Application May 17, 1932, Serial No. 611,907

15 Claims. (Cl. 161—19)

This invention relates to measuring devices, and more particularly to means for indicating the termination of the predetermined timing periods of telephone conversations.

5 In telephone systems it is at present customary to charge for coin box calls on a message rate basis. In the case of such calls it is sometimes necessary to charge for what is generally known as overtime. In other words, a certain 10 charge is made for each completed call lasting a predetermined period of time or less, for example, five minutes, and an overtime charge is made for each additional predetermined period of time during which the call lasts. At the 15 termination of the first and of each additional timing period the calling party is notified that if he desires to continue the call, he must deposit another coin.

It has heretofore been suggested in connection 20 with systems for timing telephone calls that an individual register be provided for each cord circuit of a telephone switchboard for timing each connection completed by the use of the corresponding cord circuit, a plurality of said registers being associated with a common, continuously rotating, driving shaft and each individual register being provided with means for controlling its operation.

One object of this invention is to provide an 30 efficient and inexpensive time indicator for use in connection with such systems. Another object is to provide such a time indicator which embodies means for automatically calling the attention of the operator to the termination of each 35 such timing period. Other objects and features of the invention will be apparent from the detailed description hereinafter set forth.

Figure 1 of the drawing is a side view of the time indicator with certain of its parts shown in 40 dotted lines; Fig. 2 is a side view of the target member, which serves also as the top of the time indicator, with parts thereof broken away to show the spring latch and the clutch control means; Fig. 3 is a side view of the lower part of 45 the time indicator with the side of the case removed; Fig. 4 is a bottom view of the time indicator in its operative condition; Fig. 5 is an enlarged detailed view of the rotating parts, the clutch means and the reset means; Fig. 6 illustrates 50 a telephone switchboard position showing the manner in which the time indicators may be associated with the equipment of a telephone system.

As shown in Figs. 1-5, the apparatus consists, 55 in general, of a case 1 which is open at the top,

a target member 2 which fits inside of case 1 and is hinged at one end to said case, a driving shaft 3, a driving gear 4, a tripping cam 5, a clutch means 6, a clutch control means 7, a spring latch 8, a hinge spring 9, and a reset spring 10. The 5 target member is hinged or pivoted at one end within the case by means of shaft 11, the sides of the target member being directly adjacent the sides of the case. Hinge spring 9 is wound around shaft 11, the upper end of said spring 10 being adapted to press against the top of the target member, and the lower member thereof being adapted to press against the bottom of case 1. By reason of this arrangement hinge spring 9 tends to cause the front end of the target member 15 to protrude above the front of the case as shown in Fig. 1. Near the bottom of the case is a bar member 12 which extends toward the center of said case and is so positioned with respect to spring latch 8 that when the target member is 20 pressed down said spring latch engages said bar member. The movement of the target member in being pressed down compresses hinge spring 9. As a result, when the target member is pressed down and spring latch 8 engages bar member 12, 25 the target member is held down in opposition to the force exerted by hinge spring 9. It can be seen from an inspection of Fig. 1 that said target member is exposed to view when it protrudes from the top of case 1, and is hidden from view 30 when it is pressed down to its normal position within said case.

Driving shaft 3 is adapted to be rotated continuously at a constant speed, for example, by means of a synchronous motor such as that disclosed, for example, by Patents Nos. 1,283,432, 35 1,283,433 and 1,283,435 issued to Henry E. Warren on October 29, 1918. Driving gear 4 is mounted on shaft 3 and is adapted to rotate therewith. Tripping cam 5 is fastened to one 40 end of hub 13 which in turn is loosely and slidably mounted on shaft 3. Spring 14 is wound around shaft 3 between gear 4 and cam 5, and normally keeps said gear and said cam from engaging each other. Both gear 4 and cam 5 45 are of the crown gear type—that is, the teeth protrude from the inner faces thereof. Fastened to the periphery of cam 5 is a tripping member 15. This tripping member is adapted to rest normally against bar member 12 which acts as 50 a stop therefor when cam 5 is being restored to its normal position.

Clutch means 6 is in the form of a ribbon spring. One end 16 thereof partially encircles 55 shaft 11 and is held firmly against one side of

target member 2 by means of hinge spring 9. The other end 17 of said clutch means encircles shaft 3 at a point adjacent collar 18 of hub 13. Intermediate the ends 16 and 17 the spring 5 forming the clutch means is bent outwardly to form a flange 19.

Clutch control means 7 is T-shaped with one end of the top member being bent upwardly as shown at 22 in Figs. 1 and 2. The vertical member thereof extends downwardly through a slot in the top of target member 2 and is pivoted to the sides thereof at 20. The lower part of said vertical member is grooved so that it is capable of fitting over flange 19 of clutch means 6. This groove is indicated at 21 in Figs. 2 and 4. Control means 7 is mounted on the target member in such position that end 22 can be pressed down by the same movement by which said target member is pressed down and in such position that the vertical member thereof is normally adjacent flange 19 of clutch means 6.

The reset means consists of coil spring 10 wound around hub 13 between collar 18 and cam 5. One end of spring 10 is fastened to cam 5, and the other end is fastened to bar 23 of clutch means 3.

As stated above, Fig. 6 illustrates the manner in which the time indicator may be used in connection with the equipment of a telephone system for measuring overtime on coin box calls. In said figure, 24 indicates the primary line jacks, 25 the multiple answering jacks, 26 the outgoing trunk jacks or the subscriber's multiple jacks, depending upon the particular type of switch board, 27 the plugs of the cord circuits, 28 the cord supervisory lamps, 29 the coin control keys, and 30 the ringing and listening keys. The time indicators indicated at 31 are mounted side by side on the top of the key shelf, each time indicator being in alignment with the plugs of the cord circuit with which it is to be used. It will be noted by reference to Figs. 4 and 5, that the driving shaft 3 of each time indicator has a male and a female end. When the time indicators are mounted side by side on the key shelf, the male end of shaft 3 of each time indicator is fitted in the female end of the shaft of the adjacent register. As a result, the several shafts of the time indicators form a common driving shaft 50 which is divided into a plurality of sections with male and female ends, one section for each register. By reason of this arrangement any number of time indicators may be used for each position of the switchboard, and any time indicator 55 may be replaced or taken out at any time. The male or female end, as the case may be, of one of the terminal time indicators, is fitted in the female or male end, as the case may be, of the driving shaft of a continuously operated, constant speed motor 32, for example, which shaft is connected to the motor through suitable gearing apparatus. Hence, shaft 3 and gear 4 of each time indicator rotate continuously at a constant speed.

For convenience, the operation of the apparatus will be described in connection with the system disclosed for measuring overtime on coin box calls. As indicated in Fig. 6, the target member of each time indicator is normally in its hidden position—that is, it is normally pressed down—and the control means is normally in its unoperated position. When the operator receives a signal from the calling party, she selects an idle one of cord circuits 27, inserts the answering plug into the proper one of line jacks 24, and ascer-

tains the number of the party desired. She then inserts the calling plug in the proper one of the multiple jacks 26, or, in case trunk jacks are provided, in one of the trunk jacks 26 which extends to an operator having access to the called party's multiple jack. When the called party answers, the originating operator presses down end 22 of control means 7. Since spring latch 8 is in engagement with bar member 12, target member 2 is held in its hidden position within case 1 in opposition to the force exerted by hinge spring 9. The operation of end 22 of control means 7 to its operated position, causes the vertical arm of control means 7 to press against flange 19 of clutch means 6 and force end 17 thereof against collar 18 of hub 13. Flange 19 slips into groove 21 of the vertical arm of control means 7 and both the clutch means and the control means are held in their operated positions. The pressure of end 17 of the clutch means 6 against collar 18 causes hub 13 and tripping cam 5 to slide along shaft 3 against the force exerted by spring 14 until the teeth of the cam engage the teeth of the rotating gear 4. Upon the engagement of cam 5 with driving gear 4, said cam begins to rotate at a constant predetermined speed with said gear and shaft 3. At this point, the shape and arrangement of the teeth of the cam and of the driving gear should be noted. By reference to Fig. 5 it can be seen that the forward edge of each tooth of the cam slopes downward, that the rearward edge of each tooth of the cam is straight or horizontal, and that the teeth of the driving gear are so shaped and arranged that they will mesh with the teeth of the cam. Consequently, if the teeth are not in exact meshing position at the moment they come in contact with each other, the teeth of the rotating gear will slide along the sloping edges of the teeth of the cam and will not cause any movement of the cam until they exactly mesh with the teeth of the cam. As a result of the shape and arrangement of the teeth, any inaccuracy in timing, due to the fact that the teeth do not at once mesh, will be in favor of the party charged. At the expiration of a predetermined interval of time cam 5 will have rotated with gear 4 to such a position that tripping member 15 will have come in contact with spring latch 8 and forced spring latch 8 away from bar member 12. Upon the disengagement of the spring latch from bar member 12, hinge spring 9 becomes effective to cause target member 2 to spring up suddenly from its hidden to its exposed position. The upward movement of the target member slides the grooved vertical arm of control means 7 off flange 19 of clutch means 6, and control means 7 returns to its normal position as shown in Figs. 1 and 2. Clutch means 6 is released and returns to its normal position. Spring 14 becomes effective to disengage cam 5 from gear 4. The rotation of cam 5 ceases and coil spring 10, which was wound up by the rotation of cam 5 with gear 4, immediately begins to unwind and cause cam 5 to rotate in the opposite direction until tripping member 15 comes in contact with bar member 12. The sudden movement of the target member from its hidden position to its exposed position, notifies the operator that the first timing period for the call has expired. The operator immediately notifies the calling party that his time has expired, and that if he desires to continue the call he must deposit another coin. If the calling party does not desire to continue the call, he disconnects and the operator upon receiving the disconnect signal takes

down the connection and operates the proper coin control key to collect the deposited coin. On the other hand, if the calling party deposits another coin, the operator in one movement presses down the corresponding target member and end 22 of control means 7. The cycle as described above, is repeated for the duration of the call.

If the call is terminated prior to the expiration of the first timing period, or of any subsequent timing period, the operator on receiving the disconnect signal takes down the connection and operates the coin control key as before, and then presses down the end of control means 7 opposite to end 22. This moves the vertical arm of control means 7 out from under flange 19 of clutch means 6. Clutch means 6 is released and cam 5 is restored to its normal position as before. Spring latch 8, however, still engages bar member 12, and target member 2 remains in its hidden position. When the cord circuit is used to complete another call the operator upon the completion of the connection presses down end 22 of the corresponding control means. This moves the grooved vertical arm of control means 7 under flange 19 of clutch means 6 and operates said clutch means as before to cause the engagement of the cam and gear to start the timing of the call.

It is obvious from the above description that the target members of the time indicators may normally be maintained in their exposed positions with ends 22 in their up positions. In such a case, when a cord circuit is used to establish a connection, the target member and end 22 of the corresponding time indicator are pressed down in one movement to start the timing of the call.

Although this invention has been described in connection with a telephone system for measuring overtime on coin box calls, it is to be understood that it may be used in connection with telephone systems for measuring other types of calls, and that the apparatus and features thereof may be used in connection with other systems than a telephone system to time any operation, without departing from the spirit and scope of the invention.

What is claimed is:

1. In combination, a motor, a plurality of rotatable elements, a common driving shaft rotated by said motor and adapted to rotate said rotatable elements, means individual to each rotatable element adapted to cause only the corresponding rotatable element to rotate with said shaft and to prevent the rotation of only said corresponding rotatable element, as desired, means individual to said latter means for controlling its operation, normally hidden means individual to each rotatable element, and means individual to and associated with each rotatable element adapted to operate only the corresponding hidden means automatically to an exposed position when the corresponding rotatable element rotates for a predetermined timing period, said corresponding normally hidden means being adapted to be reoperated manually to its hidden position after each timing period.
2. In combination, a motor, a plurality of rotatable elements, a common driving shaft rotated by said motor and adapted to rotate said rotatable elements, means individual to each rotatable element for starting the rotation of only the corresponding rotatable element with said driving shaft and for stopping the rotation of only said corresponding rotatable element, as
3. In combination, a motor, a plurality of rotatable elements, a common driving shaft rotated by said motor and adapted to rotate said rotatable elements, means individual to each rotatable element for effectively connecting and disconnecting the corresponding rotatable element and said shaft to start and stop the rotation of only the corresponding rotatable element, as desired, normally hidden means individual to each rotatable element, means individual to each rotatable element and adapted, when the corresponding rotatable element rotates through a predetermined arc, to cause only the corresponding normally hidden means to be operated to an exposed position, said corresponding normally hidden means, during its movement from its hidden position to its exposed position, operating the corresponding connecting and disconnecting means to cause the effective disconnection of the corresponding rotatable element and said shaft, and means individual to each rotatable element and operative upon such disconnection to restore the corresponding rotatable element to the position it occupied prior to its rotation.
4. In combination, a continuously operated constant speed motor, a plurality of rotatable elements adapted normally to remain stationary in predetermined positions, a common driving shaft rotated by said motor and adapted to rotate said rotatable elements, said shaft being divided into a plurality of sections, one for each rotatable element, with male and female ends, the male end of each said section being fitted into the female end of the adjacent section, clutch means individual to each rotatable element for effectively connecting the corresponding rotatable element with said driving shaft to start the rotation of the corresponding rotatable element and for effectively disconnecting the corresponding rotatable element therefrom to stop said rotation, as desired, control means individual to each rotatable element for operating and releasing the corresponding clutch means, a normally hidden member individual to each rotatable element, means individual to each rotatable element and adapted, when the corresponding rotatable element rotates through a predetermined arc, to cause the corresponding normally hidden member to spring suddenly into view, said corresponding normally hidden member, during its movement from its hidden position to its exposed position, releasing the corresponding control means and the corresponding clutch means to effectively disconnect the corresponding rotatable element from said driving shaft, and means individual to each rotatable element and operative upon such disconnection to restore the corresponding rotatable element to its predetermined position.
5. Means for timing the duration of telephone connections established at a central switchboard by means of a plurality of link circuits comprising, in combination, a timing device for each link circuit including a timing wheel, a driving shaft common to said timing devices and adapted to rotate the timing wheels of said timing

- devices, a motor adapted to rotate said driving shaft, means individual to each timing device for starting the rotation of the corresponding timing wheel with said driving shaft to measure the elapsed time of each telephone connection established by means of the corresponding link circuit and for stopping the rotation of only the corresponding timing wheel, as desired, normally hidden means individual to each timing device, and means individual to and associated with each timing device adapted to operate only the corresponding normally hidden means automatically to an exposed position when the corresponding timing wheel rotates for a predetermined timing period, said corresponding normally hidden means being adapted to be reoperated manually to its hidden position after each timing period.
6. Means for indicating the number of timing periods of telephone conversations on connections established at a central switchboard by means of a plurality of cord circuits comprising, in combination, a timing device for each cord circuit including a measuring wheel normally stationary in a predetermined position, a driving shaft common to said timing devices and adapted to rotate the measuring wheels of said timing devices, a continuously operated constant speed motor for rotating said driving shaft continuously at a constant speed, clutch means individual to each timing device for effectively connecting the corresponding measuring wheel with said driving shaft to start the rotation of only the corresponding measuring wheel to measure the first predetermined timing period of each telephone connection established by means of the corresponding cord circuit, control means individual to each timing device for operating and releasing the corresponding clutch means to start and stop the rotation of only the corresponding measuring wheel, as desired, a normally hidden member individual to each timing device, means individual to each timing device and adapted, when the corresponding measuring wheel rotates through a predetermined arc, to cause only the corresponding normally hidden member to spring suddenly into view, said corresponding normally hidden member, during its movement from its hidden position to its exposed position, releasing the corresponding control means to the corresponding clutch means and effectively disconnect the corresponding measuring wheel from said driving shaft, and means individual to each timing device and operative upon such disconnection to restore the corresponding measuring wheel to its predetermined position, said corresponding normally hidden member being adapted to be reoperated manually to its hidden position and said corresponding control means being adapted to be reoperated manually to start anew the rotation of said corresponding measuring wheel after each restoration of said corresponding measuring wheel to its predetermined position, to measure each succeeding timing period of each telephone connection established by means of the corresponding cord circuit.
7. A timing device comprising, in combination, a rotatable element normally stationary in a predetermined position, a driving means adapted, when said rotatable element is effectively connected therewith, to rotate said rotatable element, means for effectively connecting and disconnecting said rotatable element and said driving means to start and stop the rotation of said rotatable element, as desired, normally hidden means, means associated with said rotatable element and adapted to be rotated by said driving means, means for starting the rotation of said rotatable element with said driving means and for stopping said rotation, as desired, means hidden from view when the rotation of said rotatable element begins, and means associated with said rotatable element and adapted to operate said hidden means to an exposed position when said rotatable element rotates through a predetermined arc.
8. A measuring device comprising, in combination, a driving means, a rotatable element adapted to be rotated by said driving means, means for starting the rotation of said rotatable element with said driving means and for stopping said rotation, as desired, means hidden from view when the rotation of said rotatable element begins, and means associated with said rotatable element and adapted to operate said hidden means to an exposed position when said rotatable element rotates through a predetermined arc.
9. Measuring apparatus comprising, in combination, a rotatable element normally stationary in a predetermined position, a driving means adapted, when said rotatable element is effectively connected therewith, to rotate said rotatable element, means for effectively connecting and disconnecting said rotatable element and said driving means to start and stop the rotation of said rotatable element, as desired, normally hidden means, means associated with said rotatable element and adapted, when said rotatable element rotates through a predetermined arc, to cause said normally hidden means to be operated to an exposed position, said normally hidden means, during its movement from its hidden position to its exposed position, operating said connecting and disconnecting means to cause the effective disconnection of said rotatable element and said driving means, and means operative upon such disconnection to restore said rotatable element to its predetermined position.
10. A measuring device comprising, in combination, a driving shaft adapted to rotate continuously at a constant speed, a gear rotated by said driving shaft, a driving means for rotating said driving shaft continuously at a constant speed, a measuring wheel normally stationary in a predetermined position and adapted to be rotated by said gear when said wheel and said gear are in engagement with each other, clutch means for causing the engagement of said wheel and said gear and thus causing the rotation of said wheel by said gear, control means for operating and releasing said clutch means to start and stop the rotation of said measuring wheel, as desired, a member associated with said control means and adapted to be hidden from view when said control means is operated, means associated with said measuring wheel and adapted, when said measuring wheel rotates through a predetermined arc, to cause said member to spring suddenly into view, said member, during its movement from its hidden position to its exposed position, releasing said control means and said clutch means to disengage said measuring wheel and said gear, and means operative upon said disengagement to restore said measuring wheel to its predetermined position.
11. A measuring device comprising, in combination, a case which is open at the top, a target member positioned within said case and hinged at one end of said case, a hinge spring tending to cause the opposite end of said target member

to protrude from the top of said case, a driving shaft adapted to rotate continuously at a constant speed, a gear within said case rotated by said driving shaft, a driving means for rotating said driving shaft continuously at a constant speed, a tripping cam normally stationary in a predetermined position and adapted to be rotated by said gear when said cam and said gear are in engagement with each other, clutch means 5 for causing the engagement of said cam and said gear and thus causing the rotation of said cam with said gear, a bar member fastened to said case, a spring latch connected to said opposite end of said target member and adapted, when said opposite end is pressed down, to engage said bar member and hold said opposite end within said case against the force exerted by said hinge spring, control means mounted on said target member for operating and releasing said clutch 10 means to start and stop the rotation of said cam, as desired, a tripping member connected to said tripping cam and adapted, when said cam is rotated through a predetermined arc, to disengage said spring latch from said bar member and permit said opposite end of said target member 15 to be operated to a protruding position above the top of said case, said opposite end of said target member, during its movement to its protruding position, releasing said control means and said clutch means to disengage said cam and said gear, and means operative upon such disengagement to restore said cam to its predetermined position.

12. A time indicator comprising, in combination, a case which is open at the top, a target member positioned within said case and hinged at one end to said case, a hinge spring tending to cause the opposite end of said target member to protrude from the top of said case, a driving shaft adapted to rotate continuously at a constant speed, a crown-gear within said case mounted on and rotated by said driving shaft, a driving means for rotating said driving shaft continuously at a constant speed, a crown-gear 20 tripping cam rotatably and slidably mounted on said shaft adjacent said gear, clutch means associated with said cam for causing said cam to engage said gear and be rotated thereby, the teeth of said cam and of said gear being of such shape with respect to each other that said cam does not begin to rotate until said teeth fully mesh, a bar member fastened near the bottom of said case and extending toward the center thereof, a spring latch connected to said opposite end of said target member and adapted, when said opposite end is pressed down, to engage said bar member and hold said opposite end within said case against the force exerted by said hinge spring, control means mounted on said target 25 member for operating and releasing said clutch means to start and stop the rotation of said cam, as desired, said control means being mounted on said target member in such a position that it can be operated by the same movement by which said opposite end of said target member is pressed down, a tripping member connected to said tripping cam and adapted, when said cam is rotated through a predetermined arc, to disengage said spring latch from said bar member and permit said opposite end of said target member 30 to be operated to its protruding position above the top of said case, said opposite end of said target member, during its movement to its protruding position, releasing said control means and said clutch means, a spring mounted on said

shaft between said gear and said cam and operative upon the release of said clutch means to disengage said cam from said gear, and a coil spring associated with said cam and operative upon such disengagement of said cam to restore said cam to the position which it occupied prior to its rotation.

13. A measuring device comprising, in combination, a case which is open at the top, a target member positioned within said case, one end 10 of said target member being fastened within said case and the opposite end thereof being adapted, when released, to protrude from the top of said case, a rotatable element within said case, a driving means adapted to rotate said rotatable element, means for starting and stopping the rotation of said rotatable element, as desired, means associated with said rotatable element and adapted, when said rotatable element rotates through a predetermined arc, to release 15 said opposite end of said target member, and means operative upon the release of said opposite end of said target member to cause said end to operate to a protruding position above the top of said case.

14. In combination, a motor, a plurality of rotatable elements, a common driving shaft rotated by said motor and adapted to rotate said rotatable elements, means individual to each rotatable element for starting the rotation of only the corresponding rotatable element with said shaft and for stopping the rotation of only said corresponding rotatable element, as desired, normally hidden means individual to each rotatable element, and means individual to each rotatable element and adapted, when the corresponding rotatable element rotates through a predetermined arc, to cause only the corresponding normally hidden means to be operated to an exposed position, said corresponding normally hidden means, during its movement from its hidden position to its exposed position, operating the corresponding connecting and disconnecting means to cause the effective disconnection of the corresponding rotatable element and said shaft. 25

15. Means for timing the duration of telephone connections established at a central switchboard by means of link circuits comprising in combination, a plurality of timing devices, one for each link circuit, a driving shaft common to said timing devices and adapted to operate said timing devices when said timing devices are effectively connected thereto, a motor for rotating said common shaft, means individual to each timing device for effectively connecting and disconnecting 30 only the corresponding timing device with said driving shaft to start the corresponding timing device into operation for measuring the elapsed time, in terms of predetermined timing periods, of each telephone connection established by means of the corresponding link circuit and to stop the operation thereof, as desired, normally hidden means individual to each timing device, and means individual to each timing device and adapted, when the corresponding timing device 35 operates for a predetermined timing period, to cause only the corresponding normally hidden means to operate to an exposed position, said corresponding normally hidden means, during its movement from its hidden position to its exposed position, operating the corresponding connecting and disconnecting means to cause the effective disconnection of the corresponding timing device and said shaft.
